UNITED STATES PATENT OFFICE.

JAMES L. KIMBALL AND HERBERT C. WIRT, OF BOSTON, MASSACHUSETTS.

FUSE-BLOCK.

SPECIFICATION forming part of Letters Patent No. 431,062, dated July 1, 1890.

Application filed December 6, 1889. Serial No. 332,768. (No model.)

To all whom it may concern:

Be it known that we, JAMES L. KIMBALL and HERBERT C. WIRT, of Boston, county of Suffolk, State of Massachusetts, have invented an improvement in Electric Cut-Outs, of which the following description, in connection with the accompanying drawings, is a specification, like letters on the drawings representing like parts.

10 This invention relates to electric cut-outs especially adapted to be used in incandescent electric lighting, and is an improvement upon the cut-out substantially such as shown and described in United States Patent No. 407,077, granted to us July 16, 1889.

15 Our present invention is particularly applicable to main and branch cut-outs used in connection with a molding concealed or cleat-work secured to the walls of a building, and 20 has for its object to improve the construction of the same, whereby a smaller, neater, and cheaper cut-out is obtained.

25 The particular features of our invention will be pointed out in the claims at the end of this specification.

30 Figure 1 represents a branch cut-out embodying our invention; Fig. 2, a plan view of the base with the cap removed; Fig. 3, an under side view of the cap removed; Fig. 4, a side elevation of the cut-out shown in Fig. 1; Fig. 5, a top or plan view of the base of a modified form of cut-out, and Fig. 6 an under side view of the cap employed with the base shown in Fig. 5.

35 Our improved cut-out is composed of a base A, which may be of wood, porcelain, or other suitable insulation adapted to be firmly secured to a wall or ceiling of a building by screws inserted through holes 2 3 in the said 40 base, and a cap A', preferably of insulating material.

45 The base A, as shown in Fig. 2, is made oblong in shape, and is provided with end elevated portions a a', and a central bridge or elevated portion a², forming, with the raised end portion a, a slot or channel a³, and with the raised end portion a' a channel or slot, which is subdivided into two parts a⁴ a⁵ by a center piece a⁶, which may be an independent 50 piece, or it may be integral with the base. The raised end portion a is provided with

shallow longitudinal slots, in which are secured contact-pieces a⁵⁰ a⁶, the upper faces of which are substantially flush with the surface of the said end portion. One of the contact-pieces, as a⁵⁰, is extended beyond the end of the base and has secured to it, as by screw a⁸, one line-wire a⁹, while the contact-piece a⁶ is extended down into and across the slot a³, where it has secured to it, as by screw a¹⁰, the other line-wire a¹². The raised end portion a' has secured to it, as by screws b, contact-pieces b' b², having their inner ends bent downward and extended across the slots a⁴ a⁵, and the said bent ends have secured to them, as by screws b³ b⁴, line-wires b⁵ b⁶, which, as shown, are carried out to the sides of the base and extended in the direction of the length of the base substantially at right angles to the line-wires a⁹ a¹². The contact-pieces a⁵⁰ a⁶ and b' b² have co-operating with them two sets of contact-arms c c' d d', secured to the inner side of the cap c² on substantially diametrically-opposite sides thereof, as by screws c³, and having their ends extended beyond the opposite sides of the cap and each provided with a slot c⁴ to engage the shank of the screw b⁸. The contact-arms on opposite sides of the cap are electrically connected by fusible connections, preferably strips of wires d² d³, which may very readily be replaced when burned out by removing the cap, the electrical connections or wire attached to the base remaining intact and undisturbed.

55 The cut-out shown in Figs. 1 and 2 is designed to be used as a branch cut-out, the wire a⁹ a¹² being the positive and negative wires of the main circuit, and the wires b⁵ b⁶ being the positive and negative wires of the branch circuit.

60 When the cap A' is secured to the base, the circuit from the positive main line a⁹ may be traced as follows: Positive line a⁹, contact-piece a⁵⁰, contact d, fuse d², contact-arm c, contact-piece b', wire b⁵ through the lamp (not shown) to wire b⁶, thence by contact-piece b², contact-arm c', fuse d³, contact-arm d', and contact-piece a⁶ to negative wire a¹².

65 The cap A' (shown in Fig. 6) is designed to be used in connection with the base A (shown in Fig. 5) to form a main-line cut-out, the said base being provided with contact-blocks e e'

$e^2 e^3$, fitted in sockets on opposite sides of the base and having their outer faces preferably flush with the sides of the base.

The contact-blocks are provided with holes, 5 into which the ends of the wires $e^4 e^5$ are inserted and secured, as by screws e^6 .

By securing the fusible connections $d^2 d^3$ to the contact-arms attached to the cap I am enabled to make the base much smaller, thereby 10 economizing in material, space, and cost of construction, besides obtaining a much neater cut-out.

It will be noticed that the fusible connections joining the contact-arms on the cap 15 form part of the main or branch lines and afford additional protection to incandescent lamps or other devices, which may be tapped into either the main or branch lines, the said lamps or devices in practice being also provided with fuse-wires, as shown in our patent referred to.

We have herein shown, for sake of distinction, the cap of the main cut-out made larger than the cap of the branch cut-out; but in 25 practice they may, and preferably will, be made of the same size, so that they may be interchangeable.

We claim—

1. In an electric cut-out, the combination, 30 with a base provided with two sets of contact-

pieces, of a removable cap having two sets of contact-arms secured to it and each set extended beyond the said cap on its opposite sides, fusible connections joining the contact-arms on the cap and forming part of main or 35 branch lines, and means to secure the said contact-arms to the base outside the cap, substantially as described.

2. In an electric cut-out, the combination, with a base provided with a slot a^3 and slots 40 $a^4 a^5$, of a contact-piece a^{50} , extended outside the base, and to which a line-wire may be attached, a contact-piece a^6 , extended into the slot a^3 , and to which a line-wire may be secured, contact-pieces $b' b^2$, secured to the opposite end or side of the base and extended 45 into the slots $a^4 a^5$, and to which branch wires may be secured, and a cap having contact-arms secured to it and extended outside the cap, and fusible connections joining the contact-arms on the cap, substantially as described.

In testimony whereof we have signed our names to this specification in the presence of two subscribing witnesses.

JAMES L. KIMBALL.
HERBERT C. WIRT
